HOT BLAST CUPOLA

Filed Nov. 15, 1927

UNITED STATES PATENT OFFICE

WILLIAM D. MOORE, OF BIRMINGHAM, ALABAMA, ASSIGNOR TO AMERICAN CAST IRON PIPE CO., OF BIRMINGHAM, ALABAMA, A CORPORATION OF GEORGIA

HOT-BLAST CUPOLA

Application filed November 15, 1927. Serial No. 233,381.

This invention is an improvement in hot blast cupolas, and more particularly in cupolas of the sectional type.

The body of the usual cupola is composed of a shell of metal, and a lining of refractory material, the shell being an integral structure. Where apparatus is provided for circulating air, it is usually arranged to conduct the air circumferentially of the cupola. When the body is sectional, the sections are usually circular, each being a complete ring, and they are interconnected to enable the circulation of air.

In order to remove and replace a section, a zone of the cupola must be removed, leaving the upper part of the body unsupported by cupola construction during the removal and the insertion.

One of the primary objects of the present invention is the provision of a sectional construction, wherein the sections extend vertically, so that any one may be removed from the assembly without destroying the continuity of the body in its vertical dimension, and wherein the provision for the circulation of air is such as to carry the air along vertical lines.

Another object is to provide a construction wherein the provision for the vertical circulation of the air includes means to agitate and thoroughly mix the air during its passage from the bustle pipe to the tuyères.

Another object is the provision in such a cupola of a construction enabling economical installation, and economical repair and replacement.

In the drawings forming a part hereof:—

Fig. 1 is a vertical section of a part of the improved cupola.

Fig. 2 is a top plan view of the sectional portion, with a part in section.

Fig. 3 is a front elevation of one of the sections with a part of the outer wall removed.

In the present embodiment of the invention, the cupola includes the usual base, composed of a lining 1 of refractory material, and a shell 2 of metal. The tuyères open at the base, each being composed of an inner section 3 and an outer section 4, the inner section being within the shell as shown, while

the outer section is secured thereto in any suitable manner. Above the base the cupola body is composed of a plurality of sections arranged in annular formation and resting upon the base. 55

Each of the sections consists of a box like structure 5, of suitable height, and curved transversely on the radius of the cupola, the inner and outer or curved walls 6 and 7 being parallel, as are also the side walls 8. The sections are arranged as shown in Fig. 2, with the ends of the inner walls 6 abutting, and with a triangular space between adjacent side walls 8 of the adjacent sections. 60

Each section 5 has an opening 9 at its top, and another opening 10 at its bottom, the said openings being in the external wall 7 as shown. The opening 9 of each section is connected by a pipe 11 with the bustle pipe 12 to which air is delivered by the blowers in the usual manner. Each opening 10 is connected by a pipe 13 with the outer section 4 of a tuyère, the arrangement being such that air from the bustle pipe circulates through the pipes 11, through the sections, and through the pipe 13 to the tuyères. 70

In order to provide for a thorough agitation of the air, the inner and outer walls 6 and 7 of the sections are provided with baffles. The inner wall has vertical ribs 14 spaced apart from each other, and from the side walls 8, and the vertical ribs are intersected by horizontal ribs 15 at suitable intervals. The ribs 14 and 15 are of a height corresponding to approximately one-half the radial width of the sections, and the outer wall 7 is provided with transverse ribs 16 at suitable intervals, the said ribs alternating with the horizontal ribs 15 of the inner wall. Thus a very thorough agitation of the air circulating through the sections is provided for, before it passes into the pipes 13 and the tuyères. 80

The cupola is completed by the usual top indicated generally at 17 upon which rests the charging door-sill 18, and it has the usual stack or chimney not shown. Each of the openings 9 and 10 is encircled by a nipple, indicated for the two openings at 19, and about each opening radial sockets 20 are pro- 95

vided for bolt heads, to connect the pipes 11 and 13 with the sections 5.

In operation, with the cupola charged, air is supplied by the blowers to the bustle pipe, 5 and from thence circulates by way of the pipes 11, the sections, and the pipes 13 to the tuyères. In its passage through the sections, the air is thoroughly agitated, and is delivered to the tuyères in a uniformly heated 10 condition.

In the present construction, any section, if desired, may be easily removed and replaced by another, without destroying the continuity of the cupola in its vertical 15 dimension. That is, the upper part of the cupola has sufficient support on the base during the removal of any section, through the remaining sections.

What is claimed as new is:—

20 1. In cupola construction, a body composed of hollow or chambered sections arranged alongside each other with their side edges abutting, each section having openings in its outer wall at its upper and lower ends, 25 a bustle pipe encircling the sections, connections between said pipe and the upper end openings, the lower end openings adapted for connection with the tuyères.

2. In cupola construction, a body composed of hollow or chambered sections curved transversely and arranged alongside each other with their side edges abutting, each section having openings in its outer wall at its upper and lower ends, a bustle pipe 35 encircling the sections, connections between said pipe and the upper end openings, the lower end openings adapted for connection with the tuyères, each section having on its inner wall transverse and vertical intersecting baffles, and having baffles on its outer wall.

3. In cupola construction, a body composed of similar integral transversely curved hollow sections arranged with their side 45 edges abutting, each section having openings positioned to enable circulation of air vertically through the section, and having means to agitate and mix the air.

4. In cupola construction, a body composed of similar integral transversely curved hollow sections arranged with their side edges abutting, each section having openings positioned to enable circulation of air vertically through the section, and having means 55 to agitate and mix the air, each section having means to independently connect the same to a bustle pipe and to a tuyère.

5. In cupola construction, a body composed of similar integral transversely curved hollow sections arranged with their side edges abutting, each section having openings positioned to enable circulation of air vertically through the section in proximity to the 65 inner wall thereof, and means to constrain

the air to follow a sinuous course through the section.

6. In cupola construction, a body composed of similar independent vertically extending transversely curved hollow sections 70 arranged with their side edges abutting, each having means to independently connect the same to a bustle pipe and to a tuyère to conduct air through the section from a blower to the cupola, and means in each section to 75 constrain the air to follow a sinuous course.

7. In cupola construction, a body composed of similar independent vertically extending transversely curved hollow sections arranged with their side edges abutting, 80 each having means to independently connect the same to a bustle pipe and to a tuyère to conduct air through the section from a blower to the cupola, said means including baffles on the inner and outer faces of the 85 inner and outer walls, sundry of the baffles on the two walls alternating.

Signed at Birmingham in the county of Jefferson, and State of Alabama this 10th day of November, A. D. 1927.
